UNITED STATES PATENT OFFICE.

JOHN M. NICOL, OF MILL VALLEY, CALIFORNIA.

CENTRIFUGAL SEPARATOR.

Application filed August 28, 1923. Serial No. 659,727.

To all whom it may concern:

Be it known that I, JOHN MALCOLM NICOL, a subject of the King of Great Britain, a resident of Mill Valley, in the county of Marin and State of California, have invented a certain new and useful Centrifugal Separator, of which the following is a specification.

This invention relates to a centrifugal machine, and more particularly to a centrifugal machine for use in metallurgical operations for the separation of fine gold and platinum and other heavy minerals from associated fine sands, and for like purposes. This invention has as an object a centrifugal apparatus designed to separate two or more minerals or other materials from each other to provide separate products. Another object of the invention is to provide a form of apparatus that will be capable of concentrating out valuable metals such as gold and platinum from worthless associated sands or other metalliferous materials. A further object is to provide an apparatus for the treatment of sulphide minerals and the clean-up of dredging operations. Still another object of the invention is to provide an apparatus which will separate and concentrate materials by centrifugal action in such a manner that each particle is given a differential rotation during the course of the treatment so that a clean separation will be obtained. A still further object is to provide such an apparatus that will have means for regulating the amount of discharged concentrate while the machine is running, so that the finest adjustments may be made, and also to provide means for separating two or more concentrates. Further objects of the invention will appear as the following description proceeds.

While the apparatus described is intended for use in connection with metallurgical operations, it is to be understood that its structure is not peculiarly limited thereto, but may be used for centrifugal operations in the chemical industry and elsewhere where a machine of its structure is of value. While the invention may be represented in various embodiments, it is desired in the following preferred embodiment to describe a particu-

lar form of apparatus that is peculiarly adapted to certain metallurgical operations.

Accordingly the invention in its preferred embodiment is illustrated on the accompanying sheet of drawings, in which—

Fig. 1 represents a vertical central section of the centrifugal separator, and

Fig. 2 represents a modification of a part of the structure comprising the inner bowl.

In the aforesaid preferred embodiment, there is shown a main supporting frame 1 that carries an upper cross member 2 and a lower cross member 3. The upper cross member carries a removable angle bracket 4 serving as the supporting means for an upper bearing, and the lower cross member carries another removable angle bracket 5 serving to support a lower bearing, these bearings serving to support the revolving parts to be described later. There is also provided a footstep block 6 having an oil well 7 and an adjustable center pivot 8, and a preferably brass bushed central vertical bearing 9.

The main revolving member in which the centrifugal effect is produced consists of a bowl 10 into the bottom of which is screwed a footstep shaft 11 held by a set screw 12. The shaft 11 revolves freely in the bearing 9 and rests on the pivot of the screw 8, this mechanism being finely balanced so that the bowl will not revolve irregularly during operation. The said bowl is provided with two interior annular rifles 13 and 14 and a large annular concave rifflle 15 designed to contain mercury in this particular embodiment. There is also a discharge orifice 16 provided with a removable plug.

A central vertical feed pipe 17 is screwed into the bottom of the bowl 10 at a socket 18, and is provided with three openings near the said socket, one of which, 19, is shown. Said pipe 17 also serves as the driving member for the bowl 10, and for this purpose is provided with a driving pulley 20. The upper end of the pipe 17 revolves in a bearing 21 which is fitted into and held in place by a non-rotating vertical pipe 22. The latter fits into a center hole in the bracket 4, and is supported by a removable threaded collar 23. The lower end of the pipe 22

is threaded into a socket in a stationary massive ring 24, which is maintained in concentric relationship with the central revolving pipe 17 of the bowl 10 by means of a center bushing 25 serving as an inner bearing. On the outside of the fixed pipe 22 is located a simple clamp collar 26, held with set screws, and a flat disc 27 is located thereon and connected to the massive ring 24 by a short cylindrical section of pipe 28. The three members 24, 27, and 28 are joined together and supported by the pipe 22, as will be evident, thus forming a single non-rotating member, which may be termed an inner 10 guide bowl. As will be seen, this is stationary in the embodiment now being described.

Above the disc 27 is provided a ball bearing 29 on which runs an upper rotating hood bowl 30, which is suitably connected to and driven by a horizontal pulley 31 provided with a bearing 32. Said hood bowl 30 has an inner annular concave groove 33 that is provided with a number of discharge 20 openings such as 34.

It will be seen that the space between the lower bowl 10 and the upper hood bowl 30 represented by numeral 35 constitutes an annular discharge orifice for the concentrates of higher density congregating against the inside of the bowl 10, and this space 35 may be decreased or increased by manipulation of the screw 8 so that an opening as fine as $1/100''$ may be obtained. A 30 noteworthy feature of this structure is that such a fine adjustment may be made during the operation of the apparatus, thereby making it possible to obtain a clean separation during the running of the machine by observation of the nature and quality of the concentrate issuing through said opening 35. The discharge of concentrates coming through the annular opening 35 will fall into a suitably placed launder shown at 36. The concentrates lying inside of the outer ring of heavier concentrates may be made to pass out through the openings 34 and will be discharged into an outer launder shown at 37.

50 A wooden plug 38 may be inserted in the bottom of the pipe 17 to close the same below the orifices 19.

In Fig. 2 a modification is illustrated, showing a construction in which the inner bowl may be made rotatable. A cross member 2' carrying a bracket 4' supports a bearing 21' around a centrally fitted pipe 17'. A central pipe 22' is mounted over the said bearing 21' and has screwed at the upper end thereof a driving member 39 rotating from ball bearing 40. A bearing 41 inserted in the bracket 4' serves to guide pipe 22'. The latter is therefore made rotatable and consequently the corresponding massive ring and inner bowl, described in detail in

the above embodiment, will be made rotatable, all other parts of the structure being the same as in the above described preferred embodiment.

In the operation of the machine, a suitable rate of rotation is given thereto and a charge of mercury is introduced into the feed pipe 17 and passes into the bowl 10 through apertures 19. The centrifugal action causes the mercury to ascend the 75 sides of the bowl and fill the riffles 13, 14, and 15, any excess of mercury passing out through the opening 35.

The machine is driven at its critical speed so that a vertical wall of mercury will be 80 retained along the inside walls of the bowl 10 without causing any considerable quantity of this mercury to flow out through the opening 35, the purpose being to retain a 85 wall of mercury in the bowl so that heavy metals like gold and platinum will be retained therein in their metallic states, and so that aqueous mixtures of minerals will pass over the mercury and will make their 90 exit through the openings 35 and 34 respectively. After the wall of mercury has been formed, water is turned in at 17 and subsequently ore pulp or sands are introduced and passed down the pipe 17 and into the bowl 10. The centrifugal action causes the 95 aqueous mixture to ascend the annular space between the bowl 10 and the inner bowl 28. During this time the materials are separated according to their specific gravities, and are 100 arranged in concentric annular layers or columns. Consequently, by properly adjusting the width of the opening 35, the outer 105 heavier layer of concentrate may be removed while the inner layer passes on up and may be removed through the openings 34. In the present machine only two such means of removing concentrates are shown, but it will be understood that more than two 110 openings may be provided for like concentrates.

In the embodiment illustrated, three separations are effected—

(1) heavy metals such as gold and platinum imbed themselves in the mercury within the riffles, and they will be recovered when the machine is stopped and the mercury is withdrawn through the opening 16.

(2) the next heaviest remaining mineral particles will be discharged through the annular opening 35.

(3) and the tailings or least heavy minerals will be obtained through the opening 34.

The adjustability of the opening 35 permits a very fine cut-out to be obtained so that the outer layer of mineral concentrates may be almost entirely taken off without removing the other materials positioned interiorly thereof.

An especial feature of this invention consists in the inner bowl 28 which may be

either fixed or relatively rotatable as illustrated. It is not always possible during the centrifugal treatment of minerals and similar materials to get all of the heavier constituents on the outside ring of concentrates without having imbedded therein some of the lighter materials. The tendency is for the heavier particles to seek the outer circumference during centrifugal action and 5 to pin down and hold lighter particles, so that the normal tendency of the latter to escape inwardly is prevented by the strong pressure exerted by the heavier particles outwardly. The provision of the inner 10 bowl 28, however, causes a differential rotation of the particles lying between it and the inner wall of the bowl 10; in other words, the position of the particles is periodically changed by the friction of the 15 bowl 28, thereby releasing the lighter particles and allowing them to escape inwardly to their proper positions as determined by their gravities. It will be seen that for 20 thus purpose the bowl 28 may be fixed or 25 rotatable, the desideratum being to secure the relative movement between said bowl 28 and said bowl 10.

It will furthermore be seen that there is 30 provided a vertical column of mercury revolving in the form of a true cylinder, and that this cylinder of mercury is sufficiently long to provide a course of travel for the mineral particles and water moving upwardly, thereby enabling the minerals to 35 position themselves according to their gravities in concentric layers. Although the action of the centrifugal forces is very rapid, the mineral particles must nevertheless be given sufficient time in which to find their 40 proper positions. In the structure shown herein a sufficiently long course of travel is provided to produce this result, and consequently a very pure mineral concentrate may be taken off through the opening 35, the 45 purity of this concentrate being enhanced by the presence of the inner bowl 28.

The present form of machine is particularly advantageous in the treatment of fine 50 sands, clean-ups from dredging operations, and concentrating sulphide minerals. For example, it will succeed in separating fine 55 slime, galena, and sphalerite concentrates from each other, an operation which is otherwise very difficult. The machine may be used profitably to separate fine gold and 60 platinum in metallic form from fine minerals or from otherwise worthless sands.

It will therefore be evident that an apparatus 65 has been devised in such form and proportions that it will be capable of treating materials otherwise difficult of treatment, so as to recover valuable minerals therefrom in a very simple and effective manner. The presence of an upper bowl 70 makes it possible to secure a very fine ad-

justment of the first discharge opening during running of the centrifuge; and the presence of the inner bowl makes it possible to secure a differential rotation of materials undergoing treatment so that each particle 75 will, during the course of the treatment, be given a free opportunity to escape into its proper zone according to its density.

As many apparently widely different embodiments of this invention may be made 80 without departing from the spirit thereof, it is to be understood that I do not intend to limit myself to the specific embodiment thereof except as indicated in the appended claims.

I claim:

1. In a centrifugal machine, the combination of a bowl mounted for rapid rotation and having inner vertical sides provided with a concavity to hold a column of mercury, riffles in said sides below said concavity to also receive said mercury and heavy metal particles, said bowl being mounted for rapid rotation; and stationary means contacting with the inner portion of the material undergoing treatment for effecting a differential movement within a mass subjected to centrifugal force in said bowl.

2. In a centrifugal machine, the combination of a bowl mounted for rapid rotation 95 and having vertical sides provided with a shallow concavity to hold a column of mercury and free from abrupt obstruction above said mercury column, stationary means contacting with the inner portion of 100 the material undergoing treatment to effect a differential movement therein; an upper bowl mounted for rapid rotation and means for rotating it independently of the lower bowl, said bowl being fixed against vertical 105 motion; and a vertical adjustable pivot point upon which the first named bowl rotates whereby the space of the cutout between the bowls may be adjusted to any desired size.

3. In a centrifugal machine, the combination of a bowl mounted for rapid rotation and having inner vertical sides to hold permanently a vertical annular wall of mercury, riffles in said sides below said annular wall to receive mercury and heavy metal particles, said bowl being mounted for rapid rotation, and stationary means contacting with the inner portion of the material undergoing treatment for effecting a differential movement within the mass subjected to centrifugal force in said bowl.

4. In a centrifugal machine, the combination of a bowl having vertical inner sides and mounted for rapid rotation on a vertically adjustable pivot; an upper bowl mounted for rapid rotation but fixed against vertical movement, said upper bowl having an aperture for the discharge of lighter concentrates.

5. In a centrifugal machine, the combina-

tion of a bowl having vertical inner sides and mounted for rapid rotation on a vertically adjustable pivot; an upper bowl mounted for rapid rotation but fixed against vertical movement, said upper bowl having an aperture for the discharge of lighter concentrates; and stationary means contacting

with the inner portion of the material undergoing treatment to effect a differential movement therein.

In testimony that I claim the foregoing, I have hereunto set my hand this 25th day of August, 1923.

JOHN M. NICOL.
